E. A. DENNIS

ADJUSTABLE AND LOCKABLE GARMENT HANGER

Filed Sept. 20, 1924

INVENTOR
EDITH A. DENNIS

BY *Edith A. Dennis*

ATTORNEY

UNITED STATES PATENT OFFICE.

EDITH A. DENNIS, OF SAN FRANCISCO, CALIFORNIA.

ADJUSTABLE AND LOCKABLE GARMENT HANGER.

Application filed September 20, 1924. Serial No. 738,747.

To all whom it may concern:

Be it known that I, EDITH A. DENNIS, a citizen of the United States, and a resident of the city and county of San Francisco and State of California, have invented certain new and useful Improvements in Adjustable and Lockable Garment Hangers, of which the following is a specification.

This invention relates to garment hangers and in particular to adjustable and lockable garment hangers of a character designed to prevent removal or theft of garments in department stores or like places where garments are displayed for inspection by customers.

This invention is designed primarily to prevent theft of garments displayed on racks or like supports generally used for the purpose and to prevent unnecessary handling of the displayed garments by prospective customers.

The present invention combines the ordinary garment hanger, and its several improvements, with a durable locking mechanism of extremely simple, yet efficient character, which is not only a locking means for the hanger but may be adjusted to any position and automatically locked in that position.

The primary object of this invention is to provide a garment hanger of the character described that combines a simple and efficient hanger and a simple locking mechanism therefor which is adjustable and self locking.

Another object is the provision of a garment hanger that combines the garment locking feature and hanger locking feature in one lock and performs the double service of securing the garment to the hanger and the hanger to its supporting bar or rod.

Other objects and advantages of this invention will appear with reference to the subjoined specification and the accompanying one sheet of drawings, in which:

Figure 1 is a side elevation of the device showing the locking mechanism as it appears in locked position, the dot and dash positions representing the positions of the lock and the hinged arm of the hanger upon release from the locked position, preliminary to the removal of the garment from the hanger and the hanger from the supporting bar.

Fig. 2 is an elevation of the device on a smaller scale, representing one of the clamp

members as a coat hanger and the other as an ordinary clamp member, as in Figure 1.

Fig. 3 is an edge view of the device as seen looking from the right of Figure 1 and showing the lock, hinged arm and clamp members as they appear when in locked position.

Fig. 4 is a transverse sectional detail of the lock mechanism, taken at the lines 4-4 of Figures 1 and 3.

Fig. 5 is a vertical sectional detail of the lock mechanism.

Referring more particularly to the drawings, the device consists of a supporting member 1, preferably formed of heavy gauge spring wire, bent upon itself at one end to form a hook 2 and resilient supporting rods 3 and 4 which tend to spread at their lower extremities 5 and 6. Clamps 7 and 8 formed of hard wood, or like material, constitute the garment clamping members, centrally secured to the extremities of the rods 5 and 6, their ends being bent to form hooks 9 and 10, which are fitted into prepared openings in the under edges of said clamp members and at some distance to their entrant points, in order to insure rigidity of said clamp members with respect to the rods 3 and 4.

The clamp members are provided upon their inner faces with strips of felt or rubber 11 and 12, which engage portions of the garment or garments and maintain a firm grip thereon when the clamp members are pressed together by the slideable mechanism 13.

The locking mechanism consists of a block or the like 14, having openings 15 and 16 for the reception of the supporting rods 3 and 4 and a third slotted opening 17 formed at its front edge for the reception of the hinged arm 18. The opening 17 is somewhat larger in diameter than the hinged arm 18 and is provided with a counterbored upper face 19 adapted to readily engage the lower end 20 of said hinged arm 18.

The rod 3 is notched or serrated, as indicated at 21, these serrations forming stops against which the bolt, or latch, 22 of the locking mechanism engage. These serrations are of saw-toothed formation and the engaging edge of the latch 22 is accordingly shaped to engage therein and maintain the locking mechanism at any point and to allow of downward movement only thereof. The bolt, or latch, 22 may be pivoted at 23

to the upper face, or recessed within the block 14, as indicated at 24. The latch is held in engagement with the serrated face 21 by means of a spring 25 which tends to normally retain the latch in locked position. The opposite end of the latch 22 is provided with a tip 26 extending into the path of a tumbler-barrel 27 adapted to receive a key 28, the lower end of which, when inserted 10 in said tumbler-barrel and turned, will release the latch 22 from the serrations 21 of the rod 3, thereby allowing the locking mechanism to move upwardly and causing the spring rods 3 and 4 to spread and to 15 release any garment gripped between the clamp members 7 and 8.

The hinged arm 18 is hinged at one end of the hook 2 by means of an eye 29 and extends loosely through the opening 17 in the 20 block 14 and prevents the removal of the hanger from the rod or bar 30 except when the lock is released and moved to the dot and dash position 31, Figure 1, and the garment removed, and then dropped to the dot and 25 dash position indicated at 32 which frees the arm 18, so that it may be swung outwardly to release the hanger from the rod or bar.

In Figure 2 I have shown a hanger constructed in accordance with the principles 30 of my invention, except that one of the clamp members 33 is constructed in the form of a coat hanger adapted to support a coat and dress, or a coat and trousers. This construction differs only in the form of one of the clamp members, the locking mechanism being the same as that shown in the other construction and functioning in exactly the same manner.

40 It will be understood that the locking mechanism may be moved to any point to draw the supporting rods 3 and 4 together, or spread them, as the case may be, to accommodate any thickness of garment between the clamp members 7 and 8, and the further down the locking mechanism is

pressed toward the clamp members, the tighter they are drawn together, and it is then necessary to insert the key 28 to release the latch 22 before the locking mechanism 50 can be moved upwardly to free the garment. It is necessary to release the hinged arm 18, only when it is desired to remove the hanger from the bar or rod 30.

It is obvious that I have constructed a device which is positive in action, yet simple in construction, and I wish it understood that the form of lock shown and described may be varied as practice suggests without departing from the spirit and scope of my invention, as set forth in the following claims.

Claims:

1. A garment hanger comprising in combination, resilient supporting members, of locking mechanism therefor, said supporting members carrying a rod engaging hook and garment clamping members, a hinged arm mounted upon said hook and extending in parallelism with said supporting members, and said locking mechanism adapted 70 to include said resilient supporting members and hinged arm and contract said resilient members and clamp members tightly against the garment when moved toward said clamp members.

2. A garment hanger comprising, resilient supporting members carrying locking mechanism, said locking mechanism being provided with a latch member adapted to engage serrations formed in one of said supporting members, a hook element formed at one end of said supporting members carrying a hinged arm adapted to be brought into engagement with said locking mechanism, garment clamps mounted at the lower ends 85 of said supporting members; said locking mechanism adapted to contract and clamp said garment clamps when moved downwardly toward said clamps and, when moved to its extreme limit, to free said hinged arm.

EDITH A. DENNIS.
